Primary Examiner — Austin Murphy(74) *Attorney, Agent, or Firm* — Brinks Hofer Gilson & Lione(57) **CLAIM**

We claim the ornamental design for an interphone with a TV monitor, as shown and described.

DESCRIPTION

FIG. 1 is a top perspective view of an interphone with a TV monitor of the present invention;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The article is a unit of an intercom system which is used in a house. The unit has a monitor which shows an image from a camera of a door unit. The unit wirelessly communicates with the door unit.
